3 Claims

ABSTRACT OF THE DISCLOSURE

A tubular member in the form of an arc having two spaced longitudinal and curved members with an open end and a closed end, and at each free end at the open end there being a pair of components representing the first two fingers of the hands over which the stocking is applied prior to use.

BACKGROUND OF THE INVENTION

A great number of people have experienced difficulty and pain in applying their stockings and socks due to the fact that they must stretch and bend the knees, etc. There have been many suggestions in the prior art providing devices to take care of this problem but none has ever been successful nor really helpful and it is the principal object of the present invention to provide a device of the class described which is easy to use, while at the same time being very simple and inexpensive in construction and also without snagging or tearing the garment.

SUMMARY OF THE INVENTION

A tubular member is bent to form a U with a closed end and an open end and the longitudinal members thereof are bent into an arc which is closely akin to a semi-circle.

The free ends of the longitudinal curved members are flattened and are provided with two sock holders representing the first two fingers of the right hand at one end and the first two fingers of the left hand at the other end, over which the open end of the stocking or sock is draped prior to the use of the device.

Once having applied the sock to the sock holders the device is held firmly in both hands and on opposite sides of the arcuate members near the crossbar, i.e., the closed end. The circular members clear both sides of the calf of the leg and as the toes enter the stock or stocking the operator continues to follow carefully hand over hand with only a little pressure to enter into the heel; then when the hands have traveled approximately 90° the sock is pulled up about one-third of the leg. The device is then twisted to the right and left to release the sock holding device from the sock.

BRIEF DESCRIPTION OF THE DRAWINGS

FIG. 1 is a view illustrating the device without a sock applied thereto; and

FIG. 2 is a detail view illustrating the sock in position.

FIG. 3 is a detail view of the sock holding projections.

PREFERRED EMBODIMENT OF THE INVENTION

A rod or tubular member is bent into the form of a U having elongated longitudinal elements 10, 12 and a closed end or crossbar 14. The longitudinal elements 10 and 12 are bent into an arc and the free ends thereof

2

at 16 and 18 are flattened. To these flattened ends there are applied the sock holders generally indicated at 20. These are bolted or otherwise applied at the inside aspects of the flattened ends 16 and 18 to face each other. Each sock holder comprises a member having two spaced upwardly extending projections 22 which also extend outwardly away from each other as at 24 for the purpose of engaging and holding the socks. The open tops of the socks are folded over the projections which thereby hold the socks in position to be put on.

In the operation of the device a sock or stocking is positioned at its open end over the sock holders 22, 22 with the heel extending downwardly as shown. The user holds the device firmly in both hands with one hand on each longitudinal element near the top crossbar. The device then extends downwardly i.e., the concave aspect of the longitudinally elements 10 and 12 faces upwardly. These longitudinal curved elements clear both sides of the calf of the leg and since the user is grasping the device adjacent crossbar 14 he is easily capable of inserting his toes in the sock, the sock being attached to the holders 22, 22. The user then pulls up carefully hand over hand with only sufficient pressure to fully insert the toes into the toe of the sock and the heel into the heel of the sock, continually pulling up and forwardly.

When the socks are up as far as desired the device is twisted to the right and then to the left to release the sock therefrom.

It will therefore be seen that a painless way of applying socks is provided with a very inexpensive tool, easily operated by anyone with the use of his hands. The device may be made of any material but light weight tubing is especially practicable and the device is quickly and inexpensively made and easily utilized.

35 I claim:

1. A device for putting on stockings or socks comprising a pair of elongated spaced parallel elements connected at one end and spaced at the opposite end providing free ends therefor, said elements being arcuate from the connected ends thereof toward the free ends, the free ends having portions that are straight, and sock holders at the straight portion of the free ends of said elongated elements, said holders extending inwardly for a short distance toward the closed end of the device and adapted to retain a stocking or a sock thereon, with the open end of the latter folded over the holders,

said holders each including a pair of mutually spaced projections spaced from the free end portions of the elongated elements to receive the folded over open ends of the stocking or sock, said projections extending away from each other toward the said free end portions of the elongated elements.

2. The device of claim 1 wherein the holders are located at the inside aspects of the elements.

3. The device of claim 2 wherein the holders face each other.
